UNITED STATES PATENT OFFICE.

LEO V. STANDISH, OF GARDINER, MAINE, ASSIGNOR OF ONE-HALF TO WILL C ATKINS,
OF GARDINER, MAINE.

AUTOMOBILE-HEATER.

1,287,495.

Specification of Letters Patent. Patented Dec. 10, 1918.

Application filed January 11, 1918. Serial No. 211,381.

To all whom it may concern:

Be it known that I, LEO V. STANDISH, a citizen of the United States, residing at Gardiner, in the county of Kennebec and 5 State of Maine, have invented certain new and useful Improvements in Automobile-Heaters; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

5 This invention relates to a device for heating the interior of an automobile, and consists in an arrangement of parts, whereby the heat from the motor is utilized for this purpose, to the exclusion of any applied or extraneous heat generating device.

In the accompanying drawing; Figure 1, is a plan view partly in section of an automobile, illustrating the application of this invention.

25 Fig. 2, is an elevation partly in vertical section.

Fig. 3, is an enlarged view partly in vertical section illustrating the damper actuating mechanism.

30 Fig. 4, is a fragmentary longitudinal sectional view through the engine hood, taken on line 4—4 of Fig. 3, and

Fig. 5, is a similar view illustrating the same parts in different position.

35 Referring to the drawing by reference numerals:

1 indicates an automobile, 2 the motor, 3 the motor compartment, 4, the motor hood having the sides 5, and 6 is the cooling radiator through which air enters the motor compartment 3. 4' indicates the cowl, and 5' the motor pan.

6' indicates a bifurcated flue, arranged at the rear and in continuation of the motor 45 compartment 3, the branches 7 and 8 of said flue leading under the floor of the automobile body one to the front or driver's compartment, and the other to the tonneau respectively. At the termination of each 50 branch 7 and 8, is a register 9, of any approved form, through which the heated air from the branches 7 and 8 passes into the body of the car.

Disposed in the bottom 10 of the flue 6', 55 and in line with the branches 7 and 8, are

two damper openings 11, while pivoted directly behind said openings, and on a common rod 12, are two dampers 13, of a size to completely close the damper openings 11, when said dampers are in a lowered position, and of a size to completely close the branches 7 and 8, when the dampers are in a raised position, said dampers being mounted unbalanced so as to close the damper openings by gravity, the lowered position of said dampers being therefore their normal position.

Pivoted at 14, adjacent one of the dampers 13, is a lever 15, having its forward arm 16 extending forwardly of its pivot, 70 and its rear arm 17 extending rearwardly and under the contiguous damper 13, as shown in dotted lines in Fig. 3, in such manner that upon depression of the forward arm 16 of the lever 15, the rear arm 17 engages the face of the damper 13, and raises it and its fellow damper 13 into raised position shown in Fig. 3.

The sides 5 of the hood 4, are provided with the usual louvers 18, and immediately 80 behind the louvers 18 of each side 5, is a thin metal plate 19, having a plurality of vertical openings 20, capable of registering with the louvers 18 of the hood 4. Said plates 19 are provided near each end thereof with 85 an obliquely disposed slot 21, while each side 5 of the hood 4 is provided with pins and wing-nuts 22, corresponding with the slots 21 in the plates 19. By means of this construction, the plates 19 can be moved forwardly and upwardly to carry their vertical 90 slots 20 out of coincidence with the louvers 18, to close said louvers, and rearwardly and downwardly to bring said vertical slots 20 into coincidence with the louvers 18 to open 95 said louvers.

The forward arm 16, of the lever 15, projects forwardly and in the path of one of the plates 19, but lying in the path of said plate only when said plate is in a lowered 100 position, as partially shown in full lines in Fig. 3, said lever arm 16 being out of the path of the plate 19, when said plate is raised upwardly and forwardly as shown in this dotted position in Fig. 3.

105 The operation is as follows:

Air is continuously passing through the radiator 6 into the motor compartment, the circulation being generally assisted by a fan, (not shown). The air is heated by the 110

motor, and the heated air is available for heating the interior of the car, while the air can be discharged into the atmosphere if desired.

5 In order to lead the heated air into the interior of the car, the hood plates 19 are moved forwardly and upwardly, and set by the pins and wing-nuts 22, thus closing the louvers 18, and permitting the dampers 13 to 10 drop into their normal lowered position. The heated air within the motor compartment then passes into the flue branches 7 and 8, and through the registers 9, the quantity of heat passing through the registers being 15 controlled, as in all hot-air registers.

When it is desired to discharge the heated air from the motor compartment directly into the atmosphere, the hood plates 19, are moved downwardly and rearwardly, and set 20 as before, thus bringing the vertical slots 20 of said plates to register with the louvers 18 in the hood-sides 5. Upon closing the hood, one of the said hood-plates engages the forward arm 16 of the lever 15, depressing said 25 arm and raising the arm 17, which raises the dampers 13 into the position shown in Fig. 3, thus cutting off the heated air from the flue branches 7 and 8, and allowing same to be freely discharged through the louvers 30 18, and the damper openings 11.

An intermediate setting of the hood-plates 19, will obviously only partially open the louvers 18, and only partially raise the dampers 13, so that a portion of the heated 35 air will enter the branches 7, and 8, and a portion thereof be discharged into the atmosphere.

While I have shown and described a preferable application of this invention, the 40 same is susceptible to changes in the construction and the arrangement of the parts, and I consider myself clearly entitled to all such changes and modifications as fall within the limit and scope of the appended 45 claims.

What I claim is:

1. A device for heating automobiles, including in combination with the motor compartment, a bifurcated flue in rear and in continuation of said compartment, said flue comprising two branches terminating in the interior of the automobile, said flue being provided with a damper opening in communication with the atmosphere, a damper for closing said opening and for closing said branches from communication with the motor compartment, the hood of said motor compartment being provided with louvers, a member movable with respect to said louvers to cover and uncover the same, and means in association with said movable element and with said damper to be engaged by said movable element to raise said damper to discharge heat from the motor compartment into the atmosphere. 60

2. A device for heating automobiles, including in combination with the motor compartment, a flue in continuation of said motor compartment, said flue terminating in the interior of the automobile, said flue being provided with a damper opening in communication with the atmosphere, a damper for closing either said opening or said flue from communication with the motor compartment, the hood of said motor compartment being provided with louvers, a member movable with respect to said louvers to cover and uncover the same, and means in association with said movable element and with said damper to be engaged by said movable element to raise said damper to discharge heat from the motor compartment into the atmosphere. 75

In testimony thereof, I affix my signature, in presence of two witnesses.

LEO V. STANDISH.

Witnesses:

MARGUERITE E. ELDREDGE,
WILL C. ATKINS.
